UNITED STATES PATENT OFFICE

170,036

MOCCASIN

Ted J. Weiss, Dover, N. H.

Application July 10, 1952, Serial No. 20,536

Term of patent 7 years

(Cl. D7—7)

To all whom it may concern:

Be it known that I, Ted J. Weiss, a citizen of the United States and a resident of Dover, in the county of Strafford and the State of New Hampshire, have invented a new, original, and ornamental Design for a Moccasin, of which the following is a specification, reference being had to the accompanying drawing, forming a part hereof.

Figure 1 is a plan view of a moccasin embodying the new design;

Figure 2 is a side elevation of the same.

I claim:

The ornamental design for a moccasin, as shown.

TED J. WEISS.
